(57) **CLAIM**

The ornamental design for a smartwatch, as shown and described.

DESCRIPTION

FIG. 1 is a front, right and top perspective view of a first embodiment of a smartwatch, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged perspective view thereof, taken from encircled portion 9 in FIG. 1.

FIG. 10 is an enlarged perspective view thereof, taken from encircled portion 10 in FIG. 2.

FIG. 11 is a front, right and top perspective view of a second embodiment of a smartwatch.

FIG. 12 is a rear, left and bottom perspective view.

FIG. 13 is a front elevation view.

FIG. 14 is a rear elevation view.

FIG. 15 is a left side elevation view.

FIG. 16 is a right side elevation view.

FIG. 17 is a top plan elevation view.

FIG. 18 is a bottom plan elevation view.

FIG. 19 is an enlarged perspective view thereof, taken from encircled portion 19 in FIG. 11.

FIG. 20 is an enlarged perspective view thereof, taken from encircled portion 20 in FIG. 12.

The broken lines depict portions of the smartwatch that form no part of the claimed design.

The dot-dash broken lines in FIGS. 1, 2, 9, 10, 11, 12, 19 and 20 are included to show an enlarged view only and form no part of the claimed design.

1 Claim, 20 Drawing Sheets
